ELECTRICAL CONNECTION

Harry A. F. Kunasch, Fond du Lac, Wis.

Application September 5, 1944, Serial No. 552,735

4 Claims. (Cl. 173—361)

My invention relates to improvements in electrical connections of the plug-in type, the primary object in view being to provide a simply constructed, inexpensive and safe connection for plugging into the usual socket of a wall outlet box, or the like, and which is adapted for operation to project the connection away from the outlet box and out of the plug, under manual control, thereby obviating the usual arduous pulling of such connections apart in inaccessible places.

Other and subordinate objects are also comprehended by my invention, all of which, together with the precise nature of my improvements, will be readily understood when the succeeding description and claims are read with reference to the drawing accompanying and forming part of this specification.

In said drawing:

Figure 1 is a view in perspective of my improved electrical connection, in a preferred embodiment thereof.

Figure 2 is a view in longitudinal section, drawn to an enlarged scale.

Figure 3 is a view in transverse section taken on the line 3—3 of Figure 2.

Reference being had to the drawing by numerals, my improved electrical connection, as illustrated, comprises a cylindrical leading end section 1 of rigid insulation material, preferably plastic, having a front end 2 solid, with the exception of an axial bore 3 therein, and a rear cylindrical chamber 4 with an internal annular flange 5 at the rear end of the same and of said section. A pair of the usual resilient prongs 6 extend from the front end 2 at opposite sides of the bore 3 for plugging into the usual form of wall outlet socket (not shown).

An annular bearing section 7 of disc-like form, relatively smaller in diameter than the rear end of the section 1, and stepped to provide a circumferential rear flange 8 thereon is secured concentrically to the flange 5 by screws 9. The bearing section 7 is also formed of insulation plastic, and is internally of the same size as the bore 3. An insulated plunger shaft 10 is slidably mounted in the bore 3 and in the bearing section 7. A coil spring 11 on said shaft 10, within the chamber 4, and interposed between a cross pin 10' in said shaft, and said section 7, tends to project the shaft out of the front end of the section 1.

A bulb 12 of rubber open at its front end and flaring toward said end is detachably coupled at said end to the rear end of the section 1 as fol-

lows: The bulb 12 is formed with an internal annular flange 13 interposed between the flange 8 and the rear end of the section 1 and clampingly engaged by said flange 8 and said rear end of the section 1 through the medium of, the screws 9.

The bulb 12 tapers to a cord section 14 through which the usual pair of insulated leads 15 are extended and pass through the bulb 12 and through suitable apertures 16 in the bearing section 7 to be extended forwardly through the section 1 and connected to the prongs 6 in any suitable manner.

Means are provided for releasably latching the plunger shaft 10 in retracted position, in opposition to the spring 11 and comprising the following devices:

A latch rod 17 of suitable resilient material extends through the bulb 12 and the chamber 4 substantially parallel with said shaft and in laterally spaced relation thereto, one end of said rod being embedded in the front end 2 of the section 1, whereby said rod is suitably connected to the section 1, the other end of the rod 17 being similarly connected to the cord 18. A transverse aperture 18 in the bearing section 7 provides for extension of said rod 17 through said section 7, the aperture 18 being of the requisite width to permit flexing of said rod 17 away from the shaft 10. A lateral latching lug 19 on the rod 17 extends toward the shaft 10 for snap action engagement with a circumferential groove 20 provided in said shaft 10 and which registers with the lug 19 when the shaft 10 is retracted to withdraw its front end into the bore 3, and as shown in dotted lines in Figure 2. As will be clear from Figure 2, the lug 19 is disposed in the bulb 12 and is provided with an inclined end 21 adapted for coaction with the rear end of the shaft 10 during retraction of said shaft so that the rod 17 will be flexed, or bowed, for reaction to engage the lug with the groove 24.

Referring now to the operation of the invention, with the shaft 10 retracted, and latched in retracted position, in the manner already described, the prongs 6 are plugged into the usual socket, not shown, for coupling the leads 15 to a source of current. By flexing the bulb 12 laterally on the section 7, the rod 17 may be flexed or bent to disengage the latching lug 19 from the groove 20, thus releasing the shaft 10. Upon releasing the shaft 10, the spring 11 will act to force the front end of the shaft against the socket, not shown, and thereby retract the prongs 6 from said socket while at the same time project-

ing the entire connection away from the socket. By again retracting the shaft 10 and latching the same, the connection may be conditioned for re-plugging in, as will be clear.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. An electrical connection for plugging into a wall socket or the like comprising a front hollow section of rigid material provided with prongs for insertion in the socket, a rear hollow flexible section coupled to the front section for flexing laterally thereon, and means adapted to exert a thrust against said socket to withdraw the prongs therefrom comprising a plunger shaft mounted in the front section for projection and retraction, spring means in said front section for projecting the shaft, and latching means for holding the shaft retracted constructed and arranged for release by lateral flexing of said rear section.

2. An electrical connection for plugging into a wall socket or the like comprising a front hollow section of rigid material provided with prongs for insertion in the socket, a rear hollow flexible section coupled to the front section for flexing laterally thereon, and means adapted to exert a thrust against said socket to withdraw the prongs therefrom comprising a plunger shaft mounted in the front section for projection and retraction, spring means in said front section for projecting the shaft, and latching means for holding the shaft retracted constructed and arranged for release by lateral flexing of said rear section comprising a flexible reactive latching rod in said sections having opposite ends anchored to said sections, respectively, for flexing with the flexible section.

3. An electrical connection for plugging into a wall socket or the like comprising a front hollow section of rigid material provided with prongs for insertion in the socket, a rear hollow flexible section coupled to the front section for flexing laterally thereon, and means adapted to exert a thrust against said socket to withdraw the prongs therefrom comprising a plunger shaft mounted in the front section for projection and retraction, spring means in said front section for projecting the shaft, and latching means for holding the shaft retracted constructed and arranged for release by lateral flexing of said rear section comprising a flexible reactive latching rod in said sections having opposite ends anchored to said sections, respectively, for flexing with the flexible section, and coacting devices on said shaft and rod interlocking with a snap action when the shaft is retracted and by reaction of said rod.
- 5 10 15 20 25 30 35 40
4. An electrical connection for plugging into a wall socket or the like comprising a front hollow section of rigid material provided with prongs for insertion in the socket, a rear hollow flexible section coupled to the front section for flexing laterally thereon, and means adapted to exert a thrust against said socket to withdraw the prongs therefrom comprising a plunger shaft mounted in the front section for projection and retraction, spring means in said front section for projecting the shaft, and latching means for holding the shaft retracted constructed and arranged for release by lateral flexing of said rear section comprising a flexible reactive latching rod in said sections having opposite ends anchored to said sections, respectively, for flexing with the flexible section, and coacting devices on said shaft and rod interlocking with a snap action when the shaft is retracted and by reaction of said rod, comprising a cam lug on the rod, and a circumferential groove in said shaft.

HARRY A. F. KUNASCH.
